UNITED STATES PATENT OFFICE.

FRANK FOOTE, OF MYSTIC, CONNECTICUT.

COIN-ACTUATED VENDING-MACHINE.

SPECIFICATION forming part of Letters Patent No. 496,780, dated May 2, 1893.

Application filed December 17, 1892. Serial No. 455,527. (No model.)

To all whom it may concern:

Be it known that I, FRANK FOOTE, a citizen of the United States, residing at Mystic, New London county, Connecticut, have invented 5 certain new and useful Improvements in Coin-Actuated Vending-Machines, which improvements are fully set forth and described in the following specification, reference being had to the accompanying seven sheets of drawings.

10 This invention is in "coin actuated machines" for vending cigars and has for its object to provide a mechanism of comparatively simple construction by means of which cigars may be automatically sold directly from the 15 box in which they are originally packed and stamped as at this time required by the United States revenue laws.

The drawings hereto annexed assist materially in explaining my invention, Figure 1 20 being a front elevation of a coin actuated vending machine embodying said invention and Fig. 2 a side view of the same with its casing partly cut away to expose the path followed by the coin in its passage through 25 the machine. Fig. 3 is a rear end elevation of said machine and Fig. 4 is a central, vertical sectional view of the same as if cut from front to rear, showing the delivery drawer open to deliver a single cigar. In Fig. 5 I 30 have illustrated detached from the casing of the machine said delivery drawer and the belt by means of which the cigars are transferred, one at a time, from the hopper to the said drawer. Fig. 5^a is a detached view of a 35 pawl carried by said drawer and employed to move said belt as hereinafter explained. Fig. 6 is a plan view of said belt mounted upon its supporting frame, which latter is shown in plan, detached in Fig. 7. Fig. 8 is an inner 40 face view of one of the side casings of my machine and Fig. 9 is a view similar to Fig. 4, with the delivery drawer closed, illustrating the manner of unloading a box of cigars into the machine. Fig. 10 shows plan and 45 end views of one of two rollers provided to assist in guiding the cigars in proper direction as they pass downward into the machine. Figs. 11 and 12 are, respectively, top and bottom views of the delivery drawer, its pawls 50 for moving the belt shown in Fig. 5^a and certain springs which force said drawer outward when unlocked by the entrance of a coin. Fig. 13 is a top view of the complete machine with the delivery drawer opened. Figs. 14

and 15 are side views of a portion of said machine, cut away to show the path of the coin, said coin being shown as just entered in the slot in Fig. 14, while in Fig. 15 it is illustrated as having passed downward upon the latch that holds the delivery drawer and as having 55 been pressed down to release said latch. In Fig. 16 are shown top and side views of the escutcheon and slot through which the coin is dropped, and of the pendent rod or wire by means of which said coin is forced down upon 60 the drawer latch to release the latter. Figs. 17 and 18 are views similar to Figs. 14 and 15 but show a slightly different form of slot by means of which a multiple of coins may be employed instead of a single one, as in the 65 preceding figures.

My invention may be briefly described as a box having a hopper in which may be placed an ordinary cigar box, and having also mechanism by means of which a single cigar may 70 be deposited in the spring actuated drawer, which drawer may be unlocked only by dropping a coin of given size into a slot in said machine. To produce these results, various 75 novel mechanisms have been provided and 80 combined, as I will explain in detail.

Referring to the drawings 20 and 21 denote the sides of the casing of my machine made preferably of metal and connected at top and bottom (both at the front and rear) by crossbars 85 22-23. The inner confronting faces of the sides 20-21, as here shown, are formed with grooves 24, 25, 26, 27, 28, 28', 29 and 30, each of said grooves being provided for an important purpose. Groove 24 is made to receive 90 a plate 31 upon which the cigar box rests when first placed in or over the hopper of the machine as illustrated by Fig. 9 in which 32 indicates the cigar box and 33 the bottom of said box.

Before placing the cigar box in the vending machine the cover of said box is loosened so that it may be readily removed and the box is then inverted and placed in the upper end or hopper of the machine, with the loosened 100 cover (which then becomes the bottom of the box) resting upon the plate 31 which latter may be provided upon its upper face with one or more small pins 34 which readily enter the box cover when the latter is pressed down 105 upon them.

When the plate 31 is drawn out from its grooves 24 it carries with it the box cover (see

Fig. 9) thus opening the lower portion of the box and permitting the cigars to fall upon an endless belt or chain 35 which is mounted upon rollers 36 supported in a frame 37 that is supported in the slots 26. Belt 35 is formed with a number of cross bars 38 located at such distances apart that a cigar may easily drop between them (see Fig. 4). At each end of the machine is a roller 39 supported in a frame 40 that is of proper size to slip easily into the slots 25 and so located that the rollers 39 are immediately over the rollers 36 upon which the belt is mounted. The rollers 39 serve to prevent more than one cigar from passing downward around the end of said belt and also serve (by rolling and agitating the cigars in the hopper) to cause the cigars to feed downward upon the belt as the latter moves forward to deposit a cigar in the delivery drawer. As the belt is moved forward it gives a rotary movement to the lower row of cigars and these in turn impart a similar movement to nearly all the cigars in the hopper, as well as to the rollers 39, thus disturbing the entire lot of cigars and insuring their dropping upon the belt to take the places of those carried by said belt to the delivery drawer 40'. Said drawer is about one half the length of the complete vending machine and slides in the grooves 27. A diagonal partition 41 near the outer end of the drawer 40' provides a long narrow chamber 42 of suitable size to receive a cigar and one of the end walls of said chamber is cut through to provide an opening 43 through which the cigar may be slid endwise. When the drawer is closed the partition 41 lies beneath the front belt roller 36 in such position that a cigar carried around with said belt will certainly drop into the chamber 42. Pivoted to each side of drawer 40' is a pawl 44 whose free end extends rearward and is adapted to engage successively the cross bars 38 of the belt as the drawer 40' is closed after each delivery of a cigar, to move the belt forward a distance equal to the movement of the drawer, and thus carry another cigar along to a point where it may drop into chamber 42 just as the drawer is closed. A suitable spring 44' should be provided to hold the free ends of the pawls 44 in engagement with the cross bars 38. This spring may consist of a thin flat piece of flexible material secured at its central portion to the bottom of the drawer, and having its free ends projecting over the free ends of the pawls. Drawer 40' is forced outward by a peculiarly formed spring 45 best illustrated in Figs. 11 and 12 of the drawings. This spring is formed of a single piece 60 of wire secured near its middle portion to a plate 46 that is slid into the grooves 28 from the rear end of the machine. Said wire is then bent to cross itself as in Fig. 12 and its ends are attached to the rear wall of the delivery drawer. This spring, in its efforts to expand, seeks constantly to force said drawer outward but ordinarily said drawer is locked

in the closed position by a spring latch 46' attached to its side and which hooks under the end of a piece 47 secured to the side casing 21 (see Figs. 2, 14, 15, 17 and 18). This spring latch 46' lies in a pathway 48 formed in said side casing, through which the coin passes on its way downward to a drawer 49 that slides in the grooves 28'. The entrance to 75 said pathway is preferably over the spring latch but said path deflects from a right line, being shown here as curved, so that after the coin has been deposited therein it cannot readily be "fished" out again, neither can 80 wires or similar implements be inserted for the purpose of surreptitiously unlocking the delivery drawer.

At the entrance to the pathway 48 is a plate 50 of metal, having a slit just large enough to receive the coin and allow it to pass downward into said pathway. The plate 50 has a depending wire 51 that is of such length that its lower end will just allow the coin to enter between it and the spring latch 46'. So soon as the coin has rolled down upon the latch, the slotted plate 50 is pressed downward when the wire 51 pressing upon the coin causes the latter to push the latch downward (see Fig. 15) thus releasing its end from engagement 95 with the piece 47 and allowing the spring 45 to force the delivery drawer open. Said drawer is limited in its outward movement by a wire link 52 that is secured by a screw 53 to the plate 46. Said link straddles a pin 54 in the delivery drawer as best seen in Figs. 11 and 12 and when said drawer is forced open this pin serves as a stop when engaged by the bend at the end of the link.

Within the vertical grooves 29 at the front end of the machine, I slide a plate 55 which, it should be noticed, passes downward behind the front frame 40 and thus prevents said frame and its rollers 39 from leaving its slots 25.

Within the vertical grooves 30 at the rear of the machine I slide a plate 56 that serves to lock the rear frame 40 and its roller in place and also prevents the removal or displacement of the plate 46 to which the spring 45 is secured.

Many of the details of construction of my described machine could be changed without departing from the spirit of my invention, but the construction as illustrated and explained is practical and the parts easily assembled and I therefore prefer it.

In Figs. 17 and 18 I have illustrated a modification of my invention in which several coins are required in the pathway 48 in order to unlock and release the delivery drawer. In these drawings the coin pathway provides a longer space between the push-pin 51 and the latch 46, the length of said space being determined by the number of coins which it 125 is desired to use.

By way of further explanation let us assume that it is desired to vend cigars at fifteen cents each. In such case space is pro-

vided for three "nickels," or five cent pieces as shown in Figs. 17 and 18, these three being sufficient, when piled upon each other as shown, to fill the pathway between the latch 5 46 (upon which they rest) and the pendent pin 51 so that when said pin is pressed downward the interposed coins assist in releasing the latch.

In Figs. 17 and 18 the pendent pin 51 is provided at its lower end with a loosely hinged extension 51' which, when the coins pass downward in the pathway is pushed by said coins aside and then swings back into a plumb position as the coins pass. After the coins 15 pass and the hinged end returns to its normal, plumb, position, said hinged end then serves as a stop to prevent the coins from being surreptitiously withdrawn from said slot.

My machine as a whole is quite simple but 20 performs its work equally as well as many machines of more complicated construction.

The operation of said vending machine is as follows:—A box of cigars is first opened and after being inverted is placed in the open 25 top of the machine, resting upon the plate 31 which latter is then withdrawn (see Fig. 9) permitting the cigars to drop upon the belt 35 and fill the spaces between the cross-bars 38 (see Fig. 4): the drawer 40 is then pushed 30 inward causing the pawls 44 to engage one of the cross-bars 38 and thus move the belt forward a distance sufficient to carry a cigar around the front end of the belt and cause it to drop into the compartment 42 just as the 35 drawer reaches its closed position. When it is desired to deliver a cigar a coin is dropped through the slot of plate 50 and passes downward until it is stopped by the latch 46. Plate 50 is then pressed downward, when its dependent wire 51 (or if preferred an interposed 40 spring 57) acting through the coin, releases the latch and allows the delivery drawer to be forced outward by its actuating spring. After the cigar has been removed from the 45 chamber 42 the drawer is pushed in again and the pawls 44 again move the belt forward to drop another cigar. The coin after having released the latch, passes downward through the pathway into the lower or money drawer 49.

50 Having described my invention, I claim—
1. In a coin-vending machine, in combination, a case having an open top adapted to receive a cigar box and to serve as the hopper of said machine, and coin actuated mechanism, 55 located beneath said hopper and a removable plate above the hopper said plate being adapted to engage with and remove the cover of the cigar box when withdrawn for the purpose specified.

60 2. In combination in and with a casing having an open top adapted to receive a cigar box, a belt with cross-bars and spaces as set forth, forming the bottom wall of said hopper, and rollers 39 at each end of said hopper substantially as and for the purpose specified.

65 3. In combination in and with a casing having an open top adapted to receive a cigar

box, and having grooves 24 near the bottom of said opening, a plate 31 within said grooves, and a belt with cross-bars located beneath 70 said plate, adapted to receive the contents of said box when its cover and plate 31 are withdrawn, as specified.

4. In combination in and with a casing having an open top, and grooved sides and a 75 belt, with cross-bars, forming the bottom wall of said opening, a cigar box removably supported within said opening, a drawer in a portion of the grooves of the casing, a plate in the other grooves at the rear of the drawer a 80 spring secured to the plate for forcing the drawer out of the casing, and means for preventing the removal of the plate, substantially as and for the object specified.

5. In combination in and with a casing having an open top and having grooves 26 as set forth, a removable frame 37 located in said grooves, rollers in said frame a belt (with cross-bars) mounted upon said rollers, and means for preventing the removal of the 90 frame from the grooves substantially as and for the purpose specified.

6. The combination with a casing, of a belt having cross-bars as set forth, a sliding drawer having a compartment 42 which compartment, 95 when the drawer is closed, is beneath the delivery end of said belt, a latch for holding said drawer closed and a spring engaging said drawer in manner substantially as described and acting with a constant tendency to force 100 it (the drawer) open, said spring being formed of a single piece of wire, and permanently secured at its central portion within the casing and having its ends crossing each other and bearing against the end of the drawer. 105

7. The combination with a casing of a belt having cross-bars as set forth, a drawer located beneath the delivery end of said belt, provided with a pin a spring engaging said drawer with a constant tendency to force the 110 same open, and a stop 52 for limiting the outward movement of said drawer for the purpose specified, said stop consisting of a link, one end of which is permanently secured within the casing and the other end engages 115 with the pin on the drawer.

8. In combination with a belt having cross-bars as set forth, and a drawer located beneath the delivery end of said belt, pawls 44 secured to said drawer with their free ends 120 adapted to engage successively the said cross-bars as the drawer is opened and closed, a spring secured at its central portion to the drawer and having its free ends projecting over the free ends of the pawls for holding 125 said pawls in operative engagement with the cross-bars, and a stop 52, substantially as described for limiting the outward movement of said drawer, all for the objects specified.

FRANK FOOTE.
